UNITED STATES PATENT OFFICE.

CARL E. BROWN, OF COLUMBUS, OHIO.

AUTOMOBILE-SIGNAL.

1,371,296.

Specification of Letters Patent. Patented Mar. 15, 1921.

Application filed September 30, 1920. Serial No. 413,682.

To all whom it may concern:

Be it known that I, CARL E. BROWN, a citizen of the United States, residing at Columbus, in the county of Franklin and 5 State of Ohio, have invented a new and useful Automobile-Signal, of which the following is a specification.

This invention aims to provide novel means whereby the driver of a vehicle may 10 transmit traffic signals to the drivers of other vehicles and to pedestrians.

It is within the province of the disclosure to improve generally and to enhance the utility of devices of that type to which the 15 invention appertains.

With the above and other objects in view, which will appear as the description proceeds, the invention resides in the combination and arrangement of parts and in the 20 details of construction hereinafter described and claimed, it being understood that, within the scope of what is claimed, changes in the precise embodiment of the invention shown can be made without departing from 25 the spirit of the invention.

In the accompanying drawings:—

Figure 1 shows in elevation, a device constructed in accordance with the invention, parts being broken away;

30 Fig. 2 is a top plan; Fig. 3 is an end elevation; Fig. 4 is a top plan showing a slightly modified attaching means; Fig. 5 is a fragmental elevation showing a modified form of the invention; Fig. 6 is an end elevation showing a further modification; and Fig. 7 is a cross section of the structure shown in Fig. 6.

The numeral 1 marks a support, in the form of a plate if desired, divided at one 40 end with a jaw 2 from which projects a wing 3, a bearing 4 being formed integrally with or otherwise connected to the wing 3 and the jaw 2. The wing 3 has terminal stops 5. The wing 3 is supplied with rounded bosses 6 located closely adjacent to the stops 5.

The numeral 7 denotes a bearing having a reduced neck 8 passing through the support 1 and connected thereto in any suitable way, for instance, by way of a head 9 50 on the neck, and a washer 10 interposed between the head and the support 1. An arm 11 is mounted to swing vertically on the neck 8 and carries a transparent bull's eye 12 which may be of any desired color. A

wheel 14 is connected to the arm 11 and is journaled on the neck 8 of the bearing, the wheel abutting against the bearing. The wheel 14 has openings 15 adapted to coact with pins 16 on the periphery of a wheel 17. 60 Any suitable pinion connection may be provided, however, at the point indicated.

The wheel 17 is secured to a shaft 18 and is held thereon by a head 19 on the shaft, said shaft being journaled in the bearings 65 7 and 4, and in the wing 3. The shaft 18 is provided with a handle 28 disposed parallel to the wing 3.

A stud 20 projects from the support 1 and passes through a clamp plate 21, there being 70 a nut 22 on the stud, the nut being adapted to coact with the clamp plate. At one end, the clamp plate 21 is supplied with a flange 23 bearing against the support 1, the other end of the clamp plate carrying a jaw 24 co-operating with the jaw 2 of the support 1. 75

The device may be mounted on an automobile in various ways. For instance, it may be desirable to grip the portion 25 of the wind shield frame between the jaws 2 80 and 24, the nut 22 being tightened up for this purpose. If the signal is used on a stand, a plate 26 may be attached by securing elements 27 to the vehicle, the plate 26 having a projection 30 adapted to be engaged by the jaws 24 and 2. 85

In practical operation, rotation may be imparted to the shaft 18 by way of the handle 28, the shaft rotating in the bearings 4 and 7. The wheel 17 transmits motion to 90 the arm 11 by way of the wheel 14, and swings the arm upwardly and downwardly, signals being imparted in this manner. The light proceeding from street lamps and other sources will shine through the bull's eye 12, 95 after nightfall, and render the signal visible. When the arm 11 is swung to the limit in one direction, the arm abuts against one of the stops 5, the arm abutting against the other stop 5 when it is swung to the limit in 100 an opposite direction. The rounded bosses 6 serve to hold the arm 11 adjacent to either of the stops 5, the arm having enough resiliency so that it can pass the stops 5 when an appreciable force is applied to the arm. 105

In Fig. 5 of the drawings, parts hereinbefore described have been designated by numerals previously used, with the suffix "a". The wing 3, the stops 5 and the bosses 6 of Fig. 1 are omitted. A radial arm 30 is se- 110

cured to the wheel 14^a and carries a weight 31. The support 1^a is provided with rests 32 and 33. When the part 11^a is in a horizontal position, the weight 31 co-operates with the rest 33, whereas, when the part 11^a is in a depending vertical position, the weight 31 is in contact with the rest 32, the weight constituting means for holding the part 11^a either in an outstanding position or in a depending vertical position, as occasion may demand.

In Figs. 6 and 7 of the drawings, parts hereinbefore described have been designated by numerals previously used, with the 15 suffix "b". An arm 34 is attached to the shaft 18^b or to the wheel 17^b and carries a weight 35. One of the teeth on the wheel 17^b denoted specifically by the numeral 36, is larger than the other teeth, and there is 20 no opening on the wheel 14^b for the reception of the tooth 36. When the part 11^b hangs in a depending position, the arm 34 swings past the vertical, and rests against the upper end of the part 11^b, as shown in 25 Fig. 6, the weight 35 tending to hold the part 11^b in a depending position. When the part 11^b is in a horizontal outstanding position, as shown in Fig. 7, the tooth 36 on the wheel 17^b rests against the wheel 14^b and 30 prevents an upward swinging movement of the part 11^b, beyond the horizontal, due to the action of the weight 35, the weight 35 serving to hold the part 11^b in the position which the part 11^a occupied in Fig. 5. In 35 the construction shown in Figs. 6 and 7, the wing 3, the stops 5 and the bosses 6 of Fig. 1 are omitted.

Having thus described the invention, what is claimed is:—

1. A traffic signal comprising a support; 40 a bearing having a reduced neck mounted in the support; an arm and a wheel carried thereby, the arm and the wheel being mounted to swing on the neck, between the support and the bearing; a shaft journaled in 45 the bearing and provided with a wheel co-operating with the first specified wheel; and means for operating the shaft.

2. In a device of the class described, a support having an outstanding wing; a 50 bearing carried by the support in spaced relation to the wing; a shaft journaled in the wing and in the bearing; a handle carried by the shaft; means on the wing for holding the handle in adjusted positions; an arm 55 mounted to swing on the support; and intermeshing gear wheels connecting the shaft with the arm.

3. In a device of the class described, a support; a bearing carried by the support; 60 an arm mounted to swing on the bearing, in a plane parallel to the support; a shaft journaled in the bearing and located parallel to the support; and intermeshing gear wheels, one of which is mounted on the 65 shaft, the other of which is mounted directly on the arm.

In testimony that I claim the foregoing as my own, I have hereto affixed my signature in the presence of two witnesses.

CARL E. BROWN.
